UNITED STATES PATENT OFFICE.

JAMES H. NANGLE, OF LYNN, MASSACHUSETTS.

MACHINE FOR TRIMMING LEATHER AND OTHER FABRICS.

1,160,946.

Specification of Letters Patent. Patented Nov. 16, 1915.

Application filed December 22, 1913. Serial No. 808,085.

To all whom it may concern:

Be it known that I, JAMES H. NANGLE, a citizen of the United States, and resident of Lynn, in the county of Essex and State of Massachusetts, have invented certain new and useful Improvements in Machines for Trimming Leather and other Fabrics, of which the following is a specification.

The present invention relates to a machine designed for trimming sheets of leather or other material by cutting off the edges thereof, such machine being particularly designed and adapted to trim irregular sheets of leather and other materials such as tanned hides and skins, fabrics, and so forth, to cut off those portions of the edges which are curled back or are torn and ragged, and to cut sheets of any description to a pattern. The machine is therefore designed that it will permit the hide or other piece of leather or fabric so moved and turned that the cutting may take place in a line following the outline of the piece, or the outline of a pattern; and with feeding means which propel the hide or other sheet and also permit the sheet to be turned freely about the point of its engagement with the feeding means.

The features above mentioned are those which particularly adapt the machine to serve its designed purpose.

Other novel features of greater or less importance are also embodied in the machine as will appear in the following detailed description, and all of such features are claimed as parts of my present invention to the extent to which such features are novel and employ novel principles or novel details of constructions, arrangement, and operation.

In the accompanying drawings, Figure 1 is a side elevation of a leather cutting machine embodying my invention in the form at present best known to me. Fig. 2 is a plan view of said machine. Fig. 3 is a front elevation of said machine. Fig. 4 is a rear elevation of so much of the machine as comprises the driving mechanism for the automatically moving parts of the machine. Fig. 5 represents a detail of the machine, being a vertical section on the line 5—5 of Fig. 1 and showing the means for feeding the work. Fig. 6 is a sectional elevation of the parts at the left of line 6—6 in Fig. 1, showing a part of the feeding means and a guide for the cutter. Fig. 7 is a plan view

of the work table of the machine. Fig. 8 is a cross sectional view of said table taken on line 8—8 of Fig. 7.

The same reference characters indicate the same parts in all the figures.

The frame of the machine here illustrated comprises a base 10, a column or support 11, and a second column or upright 12, these parts serving to support the operating and driving elements of the machine and being illustrative of any means or elements which might be used for the same purposes. The base includes as a part of its structure, or has connected with it, a table 13 whereon the work 14, which is ordinarily a tanned skin or hide, but may be any other regular or irregular sheet of leather or other material, is supported with capability of movement over its supporting surface. When placed on the table in position for operation the work is gripped between feeding elements 15 and 16, of which the former is preferably a wheel having a roughened, corrugated or toothed periphery, and the latter is a disk mounted rotatably on an axis approximately perpendicular to the axis of the wheel 15 and also to the table 13, and of which the end face next to the table bears on that part of the work piece which overlies the wheel 15. The periphery of said wheel 15 projects through an opening 17 in the table, shown in Fig. 5 and is adjustable so as to project to a greater or less extent above the surface of the table.

I will here insert a description of the means for so adjusting the feed wheel. Said feed wheel is mounted rotatably on a stud 18 carried by an arm 19, which is mounted to turn on a shaft 20 as a pivot, said shaft 20 being a horizontal shaft extending from front to rear of the machine having its bearings at 21 and 22 in the opposite ends of the machine base and carrying a gear 23 for driving it. Arm 19 is thus capable of swinging up and down in a vertical plane, and it is so swung by a wedge piece 24, which projects through the front of the base, in which it is mounted with capability of sliding endwise, and has a cam or wedge surface 25 at its end underlying and engaging the arm 19 below the stud 18. An adjusting screw 26 is threaded into the front wall of the base near the wedge 24 and has a groove provided between collars which receives a fork 27 fastened to the wedge, whereby turning of the screw has the effect of moving the wedge

in or out and of correspondingly raising or lowering the feed wheel. A spring 28 is provided to put a tension on the screw and thereby produce friction between the threads of the screw and the intermeshing threads in the machine base. The feed wheel is rotated by the shaft 20 through a pinion 29 keyed upon said shaft, an idler gear 30 with which pinion 29 meshes and a gear 31 meshing with the idler 30 and fastened to the feed wheel 15. As the idler is also carried by the arm 19 and swings with the latter about the axis of the pinion 29 as a center, the described adjustments do not interrupt the continuity of the drive.

The complementary feed disk 16, which is also a presser foot is carried by a rotating upright shaft 32 which is held rotatably in bearings 33 and 34 forming part of a piece 35, which may be conveniently called for the purposes of this description a holder for the shaft 32. Said shaft is provided with an adjustable collar 36 and is surrounded by a spring 37 located between said collar and the upper bearing 33, and being placed under suitable tension by the adjustment of collar 36 so that it presses the combined feed disk and presser foot 16 upon the work. The holder 35 is pivoted to a bracket or support 38 which forms a part of the column 11, its pivot being shown at 39 and being equipped with a clamp screw 40. Thereby the holder 35 may be swung about a horizontal axis so as to alter the point in the face of the disk 16 which acts on the work. By causing more or less of the area of the disk to overlap the feed wheel, the area of the part of the work gripped thereby may be varied. The location of the pivot 39 is such that the shaft 32 is somewhat inclined to the table, whereby only that side of the disk 16 which co-operates with the wheel 15 engages the work, and those parts of the disk which travel in other directions than the feeding direction do not rub on the work.

The cutter or cutting element of the machine is a band knife 41, which passes about the guiding and driving pulleys 42 and 43, the latter pulley being below the table. Thus the band knife crosses the table, and the operating stretch travels close to the face of wheel 15 and the edge of disk 16, as appears from Figs. 1, 7, and 8. That portion of the work table immediately adjacent to the cutting and feeding elements is composed of plates 44 and 45, which cover an opening in the table and are detachably secured thereto in any desired manner, for instance, as shown in Fig. 7. Openings are left in these plates for the passage of the band knife and for the feed wheel 15 to extend through, and in the plate 45 is an undercut groove extending between the locations of the opposite stretches of the

band knife. Located in this groove is a knife holder or backer consisting of a slide 46 and an adjustable stop slide 47, secured in its adjustments by screws 48 passing through slots 49 in the stop slide into the underlying part of the plate 45. A spring 50 is between the slide 46 and the stop 48, holding slide 46 against the knife and holding the latter against a bar 51, which lies between the plates 44 and 45 and extends close to the wheel 15 and between the latter and the knife 41. The bar and backing slide 46 guide the operative part of the knife in an exactly defined location, but the slide is capable of yielding, thus allowing the knife to yield when necessary. A further guiding or steadyng device to prevent the thrust of the advancing work from displaceing the knife is provided in the form of two disks 53 mounted on a stud 54, which is carried by an adjustable arm or bracket 55 on the holder or bearing piece 35. These disks admit the back edge of the knife between them, and their hub portions, or the stud 54, engage the back of the knife at a slight distance above the location of the work, preventing the knife from yielding in consequence of the pressure of the work against its cutting edge. Instead of two disks a single disk having a peripheral groove may be used with the same effect. A spring 56 bears on one of the disks for causing the disks to engage both sides of the knife but without causing them to bind. The bracket carrying the guide disks is fastened to the bearing piece 35 by a screw 57, which passes through a slot 58 in the bracket and is threaded into the bearing piece. Still another guide, or guard, for the knife is provided to prevent the same from working off the guide pulley 42 when acted upon by a grinding wheel 59, hereinafter described, and also for holding the knife against the grinding wheel during the grinding operation. This combined guide and guard comprises a bracket 60 secured to the side of the column 11 and having two fingers 61, which are respectively on opposite sides of the plane of the grinding wheel and project close to the knife on the opposite side thereof from the grinding wheel as shown in Fig. 1. These fingers support the knife against deflection when the grinding wheel is moved over so as to bear on the edge of the knife for sharpening. The guard to prevent the knife from traveling off the pulley when acted on by the grinding wheel is a bracket or finger 62 secured to the guide and crossing the line of the knife in back of the same. It does not normally touch the knife but is in position where it will do so in case the knife should start to creep off the pulley.

Vertical adjustment of the guide pulley 42 to regulate the tension of the knife is

provided by mounting the bearing stud 63 for said pulley on a slide 64 which is set into a vertical guideway into the side of the column 11 and is capable of being adjusted. Adjustments of the slide are maintained by a screw 65 which passes through a slot 66 in the back of the column 11, is threaded into the slide 64 and has a head adapted to bind against the column and thereby to clamp the slide. A locking set screw 67 is provided to bear against the shank of the screw 65 to prevent the latter from becoming accidentally loosened.

The grinding wheel 59, before mentioned, is secured upon a short shaft 68 rotatably held in bearings 69 and 70 formed in a swinging bracket or holder 71, which has a pivotal mounting on a pin 72 mounted on the column 11. The arrangement of the bracket is such that the grinding wheel may be swung against and away from the knife. For regulating the position of the wheel and holding it against the knife I provide a lever 73, which is pivoted on a pin 74 mounted in a bracket 75 fixed to the side of the collar. Said lever has an arm 73^a adapted to press against one of the bearings of the emery wheel shaft, and a second arm 73^b equipped with an adjusting screw 76, which bears against one side of the bracket 75. The arm 73^a has a surface which acts as a cam to move the emery wheel toward the knife when the screw 76 is screwed against the bracket 75.

Power to drive the moving parts of the machine is delivered by a belt 77, which passes about a pulley 78 carried by a shaft 79, which has bearings in the post 12 and in a bracekt 80 connected to said post. Shaft 79 carries a pinion 81 which meshes with a large gear 82 wherewith is connected a pinion 83 in mesh with the gear 23, previously described as being the driver for the shaft 20. Thus the shaft and feed wheel 15 are driven at a relatively slow speed.

The same shaft drives the upper feed disk 16 by means of a pulley 84 and a belt 85 passing around said pulley, over guide pulleys 86 mounted on the post 12, and around a pulley 87 mounted loosely on the shaft 32. A friction drive is given to shaft 32 by pulley 87 through a clutch consisting of a cone 88 secured to the shaft and a socket 89 forming part of the pulley with walls tapered internally to fit the outer surface of the cone 88. The spring 90 interposed between the pulley and a head 91 fastened to the end of the shaft holds the members of the friction clutch in contact. The purpose of the clutch 60 is to permit the operator to vary the speed of feeding the leather, allowing the operator to hold back the work without causing the disk 16 to rub on the surface of the work, because slipping of the clutch allows the disk to be retarded or stopped.

The knife is driven from the shaft 79 by a pulley 92 about which passes a belt 93 running over guide pulleys 94, pivoted upon a bracket 95 secured to the rear side of the machine base, and thence around a pulley 96 fast to the shaft 97 on which the lower guiding and driving pulley 93 for the knife is fastened. 70

Another pulley 98, secured to the shaft 79 drives a belt 99 which passes over guide pulleys 100 mounted on an arm 101, extending from the bracket 75, the belt also passing around a pulley 102 secured to the shaft 68 of the grinding wheel. 75

A machine having the characteristics and elements above described is well adapted to serve the purpose of trimming the edges of irregularly shaped pieces of leather, such as skins and tanned hides, etc., or other material. The knife, being in motion continually at any speed best suited for the work in hand, cuts with a drawing action and thus constitutes the best possible means for making a clean cut and leaving the trimmed edges of the piece square and smooth. The character of the knife and the character and location relatively to the knife of the work-gripping and feeding means are important features in adapting the machine to its purpose. The knife being a band knife and having relatively very slight width in the direction of feed, and the feed wheel and complemental gripper being arranged close to the operative portion or stretch of the knife and so formed and arranged as to 90

make contact with the work over a small area, that is, making a substantially tangent contact, enable the work to be turned readily so that the cut made by the knife may follow the projections and indentations 100 of the irregular outline of the hide or other work piece. Evidently the tangent gripping contact of the feed means is the pivot point about which the work may be turned 105

or swung in the plane of the table or work support, and this pivot point is so close to the edge of the knife that such swinging or turning movement of the work takes place around the knife. The knife, owing to its slight width, permits the work to be turned 110 quickly enough for the required purpose so that the trimming cut may follow the outlines of sharp indentations without removing the good material at any considerable distance back from the edge of the work. 115 The extent of contact between the grippers and work in the direction of feeding is approximately or nearly the same as the width of the knife. 120

The means for guiding the knife consisting of the bar 51, backing piece 46, and guide disks 53 prevent the flexible band knife from being twisted or deflected in any direction when the work is pressed against it and turned while being fed. These guides, or 125

their equivalents; are adjuncts having considerable influence in adapting the machine to perform its desired function.

I desire to have it understood that in giving the foregoing illustration of my invention, I have not intended this illustration to be taken as necessarily a commercial or finished machine. So far as the essential operating parts of the machine are concerned, the embodiments of such parts here shown are operative and complete, but it is my intention to make modifications which may alter the general appearance of the machine and particularly of the frame thereof materially, but which will not be any departure from the spirit of the invention.

What I claim and desire to secure by Letters Patent is:

1. A machine for trimming the edges of sheet stock, comprising a support for the stock, a cutter arranged with its edge crossing the plane of the support, means for moving said cutter so that its edge travels in a direction transverse to the support, and work gripping and feeding means constructed to grasp the work with a tangent contact close to the cutter; the cutter having a width in the feeding direction substantially as narrow as the extent of contact of the work feeding means with the work, whereby it may be swung angularly over the support about a pivot point substantially coincident with the edge of the cutter.

2. A leather trimming machine comprising an endless band knife, and means for grasping the work at a point close to a point in the edge of said knife, operative to feed the work in a direction transverse to that in which the operating point in the knife edge travels, said grasping means having a sufficiently small area of contact with the work, and the knife being sufficiently narrow in the direction of feeding, to permit the work to be turned or swung around the knife.

3. A machine adapted to trim the edges of hides and other articles of irregular outline comprising a knife having a slight width from cutting edge to back, and means for gripping and feeding the work past the knife in the direction from the edge to the back thereof, said work feeding means being arranged to grasp the work at a point close to the knife edge, and constructed so that the area of contact with the work is relatively small, whereby to oppose the least possible resistance to turning the work about the area of gripping contact as a pivot.

4. A machine for trimming hides and the like, comprising a flexible endless band knife, means for driving said knife so that a portion of the edge thereof travels in a straight line, work gripping and feeding means located close to said portion of the

knife edge and arranged to feed the work in a direction approximately at right angles to that at which said portion travels, the knife being so narrow from edge to back and the width of contact between the work and the feeding means being so slight that the work may be turned sharply about the knife during feeding, whereby to enable the knife to follow abrupt irregularities in the outlines of the work.

5. A trimming machine comprising a work support, a band knife supported and arranged with a stretch thereof crossing said support approximately at right angles thereto, a work feeding wheel arranged below said support with its periphery projecting through the same and above the supporting surface thereof, a complementary pressing device arranged over said feed wheel to engage the upper surface of the work, guiding means in the plane of the work support engaging opposite faces of the knife, and a guide above the work support bearing against the back of the knife.

6. In a trimming machine of the character indicated, the combination with a work feeding means of an endless flexible band knife mounted with a portion thereof extending close to said feeding means and traveling in a direction transverse to that in which said feeding means is designed to feed the work, and coöperating knife guiding means located in close proximity to said feeding means arranged to engage the opposite sides and the back of the knife, respectively, to prevent twisting and other deflection thereof.

7. In a trimming machine the combination with a work support and a cutter, of a feed wheel having its periphery passing across the work support from the side thereof opposite to that against which the work lies, a movably mounted holder carrying said feed wheel, a cam member engaging said holder, and means for moving said cam member so as to effect movement of the holder in opposite directions in a line transverse to the work support.

8. In a trimming machine, a work support, a feed wheel adapted to engage the work laid against said support, a holder for said feed wheel movable back and forth in a direction transverse to the work support, a cam member operable for so moving the holder, and flexibly arranged gearing for driving the feed wheel in any of its positions of adjustment.

9. In a machine of the character described, an adjustable feed wheel, a holder in which said feed wheel is mounted, a drive shaft upon which said holder is pivoted, gearing between said drive shaft and feed wheel, and a cam or wedge supporting the swinging portion of said holder and being adjustable to raise and lower the same.

10. In a machine of the character described, a work support, a feed wheel located beneath said support with its periphery projecting through the same, a drive shaft 5 beneath the work support, an arm pivoted co-axially with said shaft and carrying said feed wheel, driving gearing between said shaft and feed wheel, maintained in mesh in all positions of the arm by reason of the coincidence of the pivot of said arm with the axis of the shaft, a wedge having a cam surface underlying and engaging said arm and means for advancing or withdrawing said wedge for causing the part of the arm 15 which carries the feed wheel to be raised and lowered.
11. A leather cutting machine comprising a cutter, a feed wheel and a complementary gripper and feeding device, said complementary feeding device being mounted on an axis approximately perpendicular to the axis of the feed wheel and arranged so that one side of its periphery overlaps the feed wheel at a point close to the cutter, said complementary gripper being also movable away from the feed wheel and being yieldingly pressed toward the latter.
12. In a cutting machine, a feeding mechanism comprising a rotatable feed wheel, a complementary feed disk rotatable in a plane approximately at right angles to the plane of the wheel and having a part of its periphery overlapping the periphery of the wheel, means for positively driving the feed wheel, and means for frictionally driving the complementary disk.
13. In a machine of the character described, the combination with a work support, or table, of a feed wheel located below the table in a plane substantially perpendicular thereto and having its periphery projecting through the table, a complementary feed disk located above the work table, a substantially vertical shaft to which said disk is connected, located so that the edge of the disk lies over the feed wheel, said shaft being so inclined that that portion of the disk over the feed wheel is nearer to the work table than any other part of the disk.
14. In a trimming machine, the combination with a work table and a feed wheel passing from below the table through an opening in the same, a complementary disk arranged over the work support in a plane nearly parallel therewith, an upright shaft carrying said disk, a holder for said shaft, and a post rising above the work support on which said holder is pivotally mounted, said holder being thereby adjustable to vary 55 the position of the disk and cause more or less of its area to overlie the feed wheel.
15. In a trimming machine, the combination with a work support and a feed wheel
- projecting across the plane of said support from beneath the same, of a complementary 65 presser and feed member comprising a disk arranged over the support and overlapping the feed wheel, a shaft to which said disk is connected rising from the feed wheel, a support by which said shaft is held with 70 ability to rotate about its axis, and frictional driving means for rotating said shaft.
16. In a machine of the character described in combination with a feed wheel, a complementary feed disk and gripper, a 75 rotating shaft by which said complementary disk is carried, so located and arranged that the disk occupies a plane approximately perpendicular to the plane of the feed wheel and overlaps the periphery of the feed 80 wheel, a holder for said shaft mounted pivotally on an axis perpendicular to the axes of both the feed wheel and the disk, whereby the distance by which the disk extends across the feed wheel may be varied.
17. In a machine of the character described, in combination with a feed wheel, a complementary feed disk and gripper, a rotating shaft by which said complementary disk is carried, so located and arranged that 85 the disk occupies a plane approximately perpendicular to the plane of the feed wheel and overlaps the periphery of the feed wheel, a holder for said shaft mounted pivotally on an axis perpendicular to the axes 90 of both the feeding wheel and the disk, whereby the distance by which the disk extends across the feed wheel may be varied, said shaft being also movable endwise in said holder and yielding means arranged to 95 press the shaft and disk toward the feed wheel.
18. In a machine of the character described, in combination with a feed wheel, a complementary feed disk and gripper, a rotating shaft by which said complementary disk is carried, so located and arranged that the disk occupies a plane approximately perpendicular to the plane of the feed wheel 100 and overlaps the periphery of the feed wheel, a holder for said shaft mounted pivotally on an axis perpendicular to the axes 105 of both the feeding wheel and the disk, whereby the distance by which the disk extends across the feed wheel may be varied, 110 a driving element for said shaft and a friction clutch connected with said driving element and to said shaft with provision for slipping.
- In testimony whereof I have affixed my 115 signature, in presence of two witnesses.

JAMES H. NANGLE.
